EUGENE S. FISHER AND ELDON R. MENDROP, OF HOLLANDALE, MISSISSIPPI.

GUARD FINGER FOR MOWING MACHINES.

Application filed December 15, 1926. Serial No. 154,965.

Our invention relates to improvements in guard fingers for mowing machines, and it consists in the combinations, constructions and arrangements herein described and 5 claimed.

An object of the invention is to obviate slipping, turning and like accidental relative movements of a guard finger relatively to its supporting bar with consequent likelihood of breakage of blades or sections of an 10 associated cutter or the cutter actuating pitman rod.

A more specific object of the invention is the provision of a guard finger which has 15 means for contacting with its supporting bar and with adjacent guard fingers so as to prevent play or slipping of the guard finger on its supporting bar.

A further object of the invention is the 20 provision of a guard finger having a portion adapted to protect the lower end of the securing means between the guard finger and its supporting bar.

Other objects and advantages of the 25 invention will be apparent from the following description, considered in conjunction with the accompanying drawings, in which

Figure 1 is a perspective view of a guard finger embodying the invention and showing 30 it in cooperative relation with a fragmentary portion of an adjacent guard finger also shown, and the supporting finger bar therefor, the latter being shown in dot and dash lines,

Figure 2 is a side elevation of the guard finger with the finger bar shown in transverse vertical section, and

Figure 3 is a section substantially along the line 3—3 of Figure 2.

A guard finger embodying the invention 40 has a forwardly tapering forward end portion 1, an intermediate portion 2 and an attaching rear end portion 3. The forward end portion 1 is of generally conventional form and is provided with a transverse slot 4 in the upper part of its rearward portion. The upper face of the intermediate portion 2 terminates at a substantial distance below the bottom wall of the slot 4 and also below 45 the upper edge of a transverse flange 5 on the upper side of the attaching portion 3 at the front end of the latter, thus defining a transverse channel above the intermediate portion 2 of the guard finger, said transverse channel having a vertical front wall 6 and a vertical rear wall 7. The inter-

mediate portion 2 of the guard finger may be rounded off transversely thereof at its sides as indicated at 8. The forward end portion of the guard finger is formed with 60 oppositely extending lateral lugs 9 at its juncture with the intermediate portion 2 so that the front wall 6 of the aforesaid transverse channel will be of relatively great area.

The rear or attaching end portion 3 of the guard finger is wider than any other portion of the guard finger and has parallel side edges as indicated at 10 and a flat horizontal upper face 11 which is located below the plane 70 of the upper edge of the aforesaid flange 5, thus producing a rearwardly facing vertical shoulder at 12. The attaching portion 3 of the guard finger is provided at its approximate center with a vertical aperture 13. The lower face of the apertured part of the attaching portion 3 of the guard finger is located above the level of the wall face of the portion of the guard finger immediately at 75 the top thereof, thus producing at the lower side of the guard finger a rearwardly facing transverse shoulder at 14.

From the foregoing description of the various parts of the device, the operation 80 thereof may be readily understood. The transverse channel above the inner portion of the tapering portion 1 is adapted for the reception of the usual ledger plates (not shown) while the channel above the intermediate portion 2 is adapted to receive an 85 overlying movable cutter bar (also not shown) from which the cutter blades carried thereby extend into the slot 4. The opposed faces of the shoulders 6 and 7 also will effectively guide the movable cutter bar during 90 its operative movements. The rear end portion 3 of the guard finger is secured by suitable fastening means, such as the bolt and nut indicated at 15 to a finger bar 16 which extends across the flat upper face 11 of the 95 rear end portion of the guard finger and has its forward edge disposed against the shoulder 12. It will be understood that a plurality of the guard fingers are secured to the same finger bar so that the side edges 10 of the 100 adjacent guard fingers will be adjacent to if not actually in contact with each other and the guard fingers thus will be prevented from swinging about the axes of their securing means 15 relatively to the finger bar. 105 The lower end portion of the securing means 15 will be disposed directly at the rear of the 110

shoulder 14 and thus will be protected by the portion of the guard finger at the front thereof against the impact of a blow from any adjacent object or against accidental injury.

Obviously, our invention is susceptible of embodiment in forms other than that which is illustrated in the accompanying drawings, and we therefore consider as our own all 10 such modifications and adaptations thereof as fairly fall within the scope of the appended claim.

We claim:—

As a new article of manufacture, a guard 15 finger for mowing machines comprising a forward end portion, an intermediate portion, and an attaching rear end portion, said forward end portion being slotted longitudinally in a forward direction from its rearward end for part of its length and having a pair of oppositely extending lateral lugs at its rearward end, said intermediate portion having its upper face terminating below the level of the bottom of the slot in the forward 20 end portion, and the top edge of a rear side wall extending parallel to the said laterally

extending lugs at the rear side of the intermediate portion thus defining a transverse channel having substantially vertical forwardly and rearwardly disposed parallel side 30 walls, said rear end portion having its upper face disposed in a plane below the top edge of the rearward side wall of said intermediate portion, said rear end portion being apertured for the reception of a fastening element and having a transversely extending rearwardly facing shoulder at the forward edge of its lower side and depending for a distance sufficient to shield and protect the lower end portion of a fastening element 40 positioned in the said aperture the transverse width of the rear end portion being slightly greater than that of the rear end of the forward end portion of the guard in the plane of the laterally extending lugs thereof, the 45 intermediate portion being of a less width than the rear attaching portion and substantially equal to that of the rear end portion of the tapered forward end portion and immediately forward of the lugs.
